Primary Examiner — Joseph Kukella*Assistant Examiner* — Darryl J Dardenne(74) *Attorney, Agent, or Firm* — Boudwin Intellectual Property; Daniel Boudwin(57) **CLAIM**

The ornamental design for an adjustable bowl, as shown and described.

DESCRIPTION

FIG. 1 shows a perspective view of an adjustable bowl; FIG. 2 shows a left side view of the adjustable bowl; FIG. 3 shows a right side view of the adjustable bowl; FIG. 4 shows a front view of the adjustable bowl; FIG. 5 shows a rear view of the adjustable bowl; FIG. 6 shows a top plan view of the adjustable bowl; FIG. 7 shows a bottom plan view of the adjustable bowl; and, FIG. 8 shows a sectional view of the adjustable bowl of FIG. 4.

The shade lines in the Figures show contour and not surface ornamentation.

1 Claim, 5 Drawing Sheets(56)
